SHEET METAL GAS BURNER

Walter Kennedy, Cliffside Park, N. J.; The United National Bank of Cliffside Park, Bergen County, N. J., administrator of said Walter Kennedy, deceased, assignor to William D. Kennedy, Englewood, N. J.

Application February 27, 1951, Serial No. 212,946

9 Claims. (Cl. 158—116)

1

This invention relates to gas burners formed from two similar, or substantially similar, sheet metal parts. More particularly, the invention deals with burners, wherein the chamber or casing portion of the burner terminates in an outwardly extending peripheral flange, the flange being corrugated angularly to the edge of the flange so as to form, on the resulting burner, angular discharge nozzles. Still more particularly, the invention deals with burners of the character described, wherein the arrangement of one burner part on top of the companion burner part, in securing said parts together, will dispose adjacent discharge nozzles in different angular relationship to each other.

The novel feature of the invention will be best understood from the following description, when taken together with the accompanying drawing, in which certain embodiments of the invention are disclosed and, in which, the separate parts are designated by suitable reference characters in each of the views and, in which:

Fig. 1 is a plan view of a part of one form of burner which I employ with part of the construction broken away in illustrating opposed angular relationship of the discharge nozzles of the burner.

Fig. 2 is an enlarged section on the line 2—2 of Fig. 1.

Fig. 3 is an enlarged detail view, looking in the direction of the arrow 3 of Fig. 1.

Fig. 4 is a diagrammatic plan view of a modified form of burner which I employ with part of the construction broken away.

Fig. 5 is a plan view of another form of burner with part of the construction broken away; and

Fig. 6 is a plan view of another form of burner which I employ, with part of the construction broken away.

In gas burners of various types and kinds, it has been customary to provide a cast burner with a series of discharge ports, or nozzles, spaced along peripheral edge portions thereof, or to form discharge nozzles between two sheet metal parts, usually of different construction, wherein the discharge nozzles are disposed at right angles to the peripheral edge of the burner.

The purpose of my invention is to provide a burner of the character described, which is formed from two similar sheet metal stampings and, in some cases, one of the stampings is modified solely for the attachment of the gas supply tube but, more particularly, my invention deals with the arrangement of the discharge nozzle passages on the flanges of the burner parts, so

2

as to be disposed angularly thereon. Thus, in arranging two similar burner parts one upon the other and securing the same together, discharge nozzles disposed angularly to each other will be arranged along the peripheral edge of the burner, so that adjacent flames will extend angularly to each other and, at the same time, be sub-divided to, at least, a slight extent to insure complete ignition of all of the nozzles and produce a continuous flame throughout the periphery of the burner.

In Figs. 1 to 3, inclusive, I have shown one adaptation of my invention, wherein the burner 10 is in the form of an elongated central tubular body 11, having an admission end 12 for introduction of the gas and a rounded closed end 13. Along the sides of the body 11 are laterally directed and opposed tubular extensions 14, having rounded ends, as at 15. The extensions 14 join the body 11 in rounded wall portions, as at 16. The complete burner is formed from two similar sheet metal parts 17, 17', these parts having peripheral flanges 18, 18' and the flanges are corrugated angularly to the edges of the flanges, particularly on the straight wall portions of the extensions 14, as illustrated in Fig. 1 of the drawing and shown in detail in Fig. 3. The corrugations form offset walls 19, 19' which, in conjunction with opposed abutting walls, 20', 20 form the gas discharge nozzles or passages 21, 21'. The portions of the walls 20, 20' which overlap between the nozzles 21, 21' can be welded or otherwise secured together. At the outer edges of the flanges, these walls abut, as indicated at 22 in Fig. 3 to subdivide adjacent nozzles 21, 21' one from the other.

By an angular arrangement of the corrugations in the manner diagrammatically indicated in Fig. 1 of the drawing, the reversing of the two similar parts 17, 17' one upon the other will reverse the angularity of the nozzles. In other words, in one part, all of the flames will be directed in one common direction as, for example, the direction of the full line arrow 23 of Fig. 1; whereas in the other part, the flame will be directed in the direction of the dotted arrow 24 of said figure. Where the corrugations extend through the rounded portions of the flanges, a somewhat wider spacing between the discharge nozzles will prevail but these discharges will be sufficiently close to facilitate complete ignition of the burner from any one position by extension of the flame in ribbon-like fashion around the flanges.

55 In this connection, it will be understood that

the particular size and angularity of the corrugations forming the resulting nozzles 21, 21' can be varied, depending upon the size and dimensions of the burner and the illustration in the accompanying drawing is simply a diagrammatic illustration.

In Fig. 4 of the drawing, I have diagrammatically shown a slight modification of the structure shown in Fig. 1 which would amount to a section of the burner shown in Fig. 1, including two of the extensions 14 and dispensing with the ends 12 and 13. In other words, a substantially H-type burner 25 is employed, wherein the two parts 26, 26' are identical, except from the standpoint that the part 26 is apertured, as seen at 27, for the reception of a fuel admission pipe for introducing gas into the burner.

In Fig. 4, the tubular extensions 28 are substantially identical with the extensions 14 of Fig. 1 and these tubular extensions are united in a central tubular portion 29. The peripheral flanges 30 will be corrugated, as with the structure shown in Fig. 1, to produce the distribution of nozzles, the same as in Fig. 1. The type of burner, shown in Fig. 4, is suitable for use in small ranges, or two of such burners could be used in a range; whereas, with the structure shown in Fig. 1, a single burner can be utilized to heat the range compartment of a gas stove.

In Fig. 5 of the drawing, I have shown a modified form of burner which is in the form of a single elongated tubular body 31, having an admission end 32 and a closed end 33, the body having, throughout the major portion of its length, a peripheral flange 34. Here again, the burner is formed from two similar parts 35, 35', having the flanges corrugated angularly to provide the nozzle discharges 36, 36'. Again, as with the construction shown in the other figures, the formation of a single sheet metal stamping is utilized to produce the resulting burner. It is preferred that the sheet metal employed be of a type and kind that will withstand the temperature and such material as stainless steel is suitable for this purpose.

In Fig. 6 of the drawing, I have shown my invention as applied to the construction of a round ring-type burner, such as generally used on the top of gas stoves for the heating of pots and pans in the preparation of food. Here again, the burner is formed from two similar sheet metal parts 37, 37', the part 37' being modified only to the extent of having an aperture 38 therein for reception of a gas supply pipe.

The burner shown in Fig. 6 has a ring-type tubular casing 39, having an inwardly extending flange portion 40, 40' and an outwardly extending flange portion 41, 41'. These flange portions are corrugated to form the discharge nozzles 42, 42' angularly disposed to each other, as with the construction shown in the other figures. The only difference in Fig. 6 of the drawing is that, instead of simply placing one sheet metal stamping directly upon the top of the other to form the resulting burner, the one stamping is rotated to a slight extent in this inversion, as will clearly appear from a consideration of Fig. 6, the purpose here being to provide a distribution of the nozzles through the entire periphery of the burner so as to distribute the flame and to insure complete ignition of the entire flame in carrying from one nozzle to the other. Here again, it will be understood that the illustration in Fig. 6 is diagrammatic in illustrating an adaptation of the invention and the size of the

corrugations and angularly thereof can be varied to produce the most desirable results in the finished burner.

Considering Fig. 1 of the drawing, it will be apparent that sufficient spacing is provided between the extensions 14 to facilitate efficient operation of the burner and this spacing also will be practical from a standpoint of producing the sheet metal stampings with a minimum of waste or by the possibility of nesting the projections or extensions 14 of one sheet with respect to those of an adjacent sheet.

Having fully described my invention, what I claim as new and desire to secure by Letters Patent is:

1. A gas burner comprising two substantially similar sheet metal parts having peripheral flanges, said parts being adapted to be arranged one upon the other with the flanges abutting and, when assembled, form a large gas supply chamber, the flanges of said parts having crossed and angularly disposed offset portions arranged throughout the full length thereof forming gas discharge nozzles, and the nozzles of one part of the burner being disposed angularly to and intermediate and longitudinally spaced from the nozzles of the other part where they discharge at the periphery of said flanges.

2. A gas burner comprising two substantially similar sheet metal parts having peripheral flanges, said parts being adapted to be arranged one upon the other with the flanges abutting and, when assembled, form a large gas supply chamber, the flanges of said parts having crossed and angularly disposed offset portions arranged throughout the full length thereof forming gas discharge nozzles, the nozzles of one part of the burner being disposed angularly to and intermediate and longitudinally spaced from the nozzles of the other part where they discharge at the periphery of said flanges, and said flanges having abutting portions intermediate said nozzles adapted to be secured together in uniting the parts of the burner.

3. A gas burner comprising two substantially similar sheet metal parts having peripheral flanges, said parts being adapted to be arranged one upon the other with the flanges abutting and, when assembled, form a large gas supply chamber, the flanges of said parts having crossed and angularly disposed offset portions arranged throughout the full length thereof forming gas discharge nozzles, the nozzles of one part of the burner being disposed angularly to and intermediate and longitudinally spaced from the nozzles of the other part where they discharge at the periphery of said flanges, said flanges having abutting portions intermediate said nozzles adapted to be secured together in uniting the parts of the burner, and the chamber formed by the parts of the burner comprising a central portion having laterally directed portions.

4. A gas burner comprising two substantially similar sheet metal parts having peripheral flanges, said parts being adapted to be arranged one upon the other with the flanges abutting and, when assembled, form a large gas supply chamber, the flanges of said parts having crossed and angularly disposed offset portions arranged throughout the full length thereof forming gas discharge nozzles, the nozzles of one part of the burner being disposed angularly to and intermediate and longitudinally spaced from the nozzles of the other part where they discharge at the periphery of said flanges, said flanges having

abutting portions intermediate said nozzles adapted to be secured together in uniting the parts of the burner, the chamber formed by the parts of the burner comprising a central portion having laterally directed portions, and one end of the burner having a projecting rounded chamber portion.

5. A gas burner comprising two substantially similar sheet metal parts having peripheral flanges, said parts being adapted to be arranged one upon the other with the flanges abutting and, when assembled, form a large gas supply chamber, the flanges of said parts having crossed and angularly disposed offset portions arranged throughout the full length thereof forming gas discharge nozzles, the nozzles of one part of the burner being disposed angularly to and intermediate and longitudinally spaced from the nozzles of the other part where they discharge at the periphery of said flanges, said flanges having abutting portions intermediate said nozzles adapted to be secured together in uniting the parts of the burner, and said nozzles being disposed at opposite sides of and at one end of said chamber.

6. A gas burner comprising two substantially similar sheet metal parts having peripheral flanges, said parts being adapted to be arranged one upon the other with the flanges abutting and, when assembled, form a large gas supply chamber, the flanges of said parts having crossed and angularly disposed offset portions arranged throughout the full length thereof forming gas discharge nozzles, the nozzles of one part of the burner being disposed angularly to and intermediate and longitudinally spaced from the nozzles of the other part where they discharge at the periphery of said flanges, said flanges having abutting portions intermediate said nozzles adapted to be secured together in uniting the parts of the burner, said chamber being circular in form, and one part being rotated in a partial revolution with respect to the other part in assemblage of said parts.

7. A gas burner comprising two substantially similar sheet metal parts having peripheral flanges, said parts being adapted to be arranged one upon the other with the flanges abutting and, when assembled, form a large gas supply chamber, the flanges of said parts having throughout the entire length thereof angularly disposed offset portions forming gas discharge nozzles, the nozzles of one part of the burner being crossed with and disposed angularly to and intermediate the nozzles of the other part where they discharge at the periphery of said flanges, said flanges having abutting portions intermediate said nozzles

adapted to be secured together in uniting the parts of the burner, and means at one end of the burner for admitting gas to the chamber thereof.

8. A gas burner of the class described, comprising two substantially similar sheet metal stampings, each stamping having a hollow portion bordered by an outwardly extending integral flange, the hollow portions collectively forming a gas chamber for the burner, the flange of each stamping being offset at longitudinally spaced intervals throughout the length thereof to form discharge nozzles on the resulting burner, the nozzles of one stamping being angularly disposed to and crossing the nozzles of the other stamping to direct the nozzle discharges of one stamping angularly to the nozzle discharge of the other stamping, the flanges having abutting portions intermediate adjacent nozzles adapted to be secured together in forming the burner, and said burner having a gas admission passage opening into the chamber thereof.

9. A gas burner of the class described, comprising two substantially similar sheet metal stampings, each stamping having a hollow portion bordered by an outwardly extending integral flange, the hollow portions collectively forming a gas chamber for the burner, the flange of each stamping being offset at longitudinally spaced intervals throughout the length thereof to form discharge nozzles on the resulting burner, the nozzles of one stamping being angularly disposed to and crossing the nozzles of the other stamping to direct the nozzle discharges of one stamping angularly to the nozzle discharge of the other stamping, the flanges having abutting portions intermediate adjacent nozzles adapted to be secured together in forming the burner, said burner having a gas admission passage opening into the chamber thereof, and the chamber of the burner having laterally extending branches arranged on opposite sides thereof.
